UNITED STATES PATENT OFFICE.

JAMES ROSS UPTON, OF PEORIA, ILLINOIS.

LOCK.

1,154,078.

Specification of Letters Patent. Patented Sept. 21, 1915.

Application filed March 8, 1915. Serial No. 12,737.

To all whom it may concern:

Be it known that I, JAMES ROSS UPTON, a citizen of the United States, a resident of Peoria, county of Peoria, State of Illinois, have invented new and useful Improvements in Locks, of which the following is a specification.

My invention relates to improvements in locks, and particularly that type of lock which is called a cylinder lock, utilizing pin tumblers to control the actuation of the cylinder in locking and unlocking.

The object in this invention is the provision of a construction permitting locks to be oiled without the possibility of the oil sealing the chambers, in which the pin tumblers are mounted to move and thereby prevent their operation, due to the formation of an air cushion behind the pin tumblers.

Further objects reside in the improvements of the construction and arrangement, which will hereinafter appear.

To the accomplishment of the foregoing and such other objects as may hereinafter appear, my invention consists in the combination, construction and arrangement of parts hereinafter described, and then sought to be defined in the appended claims, reference being had to the accompanying drawings forming a part hereof, and which shows merely for the purpose of illustrative disclosure, preferred embodiments of my invention, it being understood that various changes may be made in practice within the scope of the claims, without digressing from my inventive idea.

In the drawings;—Figure 1 represents a longitudinal section through a standard form of cylinder lock, showing the key inserted, different forms of pin tumblers being disclosed; Figs. 2, 3 and 4 represent different forms of pin tumblers coming within the purview of my invention; Fig. 5 is a horizontal section through one of the pin tumblers and a compartment therefor, showing another variation of my invention.

This invention has particular reference, as stated before, to cylinder locks, being shown in connection with a padlock of that type. These locks include a cylinder rotatably mounted therein and adapted to receive a key and having a plurality of recesses or sockets in the lock and in the cylinder to receive pin tumblers which are held toward the cylinder by means of springs. Anti-friction means in the form of balls, is

provided on top of said pin tumblers and the key is so shaped as to aline one series of the pin tumblers with the edge of the cylinder and the socket therefor, so that when the key is inserted, the cylinder may be turned to withdraw the bolt to release the shackle, it being understood that when the key is withdrawn, either partially or entirely, the lines between the pin tumblers do not aline with the edge of the cylinder and its casing and the cylinder cannot turn until the proper key is inserted. It is found in practice, that when these locks need lubrication, the application of a lubricant thereto will result in the sealing of the sockets in which the pin tumblers are mounted, so that air cushions are formed in the sockets or chambers, preventing a proper operation of the pin tumblers and therefore, putting the lock out of service. My invention was evolved for the purpose of obviating this disadvantage and consists in providing means, either in the pin tumblers or in the walls of the sockets or chambers therefor, of grooves or passages which permit the circulation and escape of air or of the lubricant, as the case may be, whereby the formation of an air or lubricant cushion is avoided.

In Fig. 1, the numeral 1 designates the lock as a whole, having the shackle 2 which is adapted to be forced outwardly by means of spring 3, and held in locked position by means of the bolt 4 and spring 5. This bolt is removed from its locked position by means of the lug 6 on the cylinder 7, this cylinder being rotatably mounted in the socket 8 in the lock. In this lock is also provided the cylinder 7' of larger diameter and fitted around said first mentioned cylinder 7. These two cylinders are provided, as is well known, for the purpose of permitting the use of the master and individual keys on locks of the same series.

9 designates the key, 10 the sockets or passages in the cylinder and 11 the sockets or passages in the lock proper, which are normally in alinement or registered with said sockets or passages 10. In these sockets or passages 10 and 11, are positioned the plurality of series of pin tumblers 12, which are preferably in the form of cylinders, as shown in detail in Figs. 2, 3 and 4, and are of different sizes, depending upon the adjustment of the lock. They are normally pressed toward the cylinder by means of

the springs 13 and have the anti-friction means in the form of balls 14, suitably held on top thereof. The key is adapted to engage the balls 14 and is shaped so as to 5 align the joints between certain series of these pin tumblers with the joint between the cylinder and its socket, as at 15, so that when the key is inserted as shown in Fig. 1, the cylinder may be turned. The lug then 10 forces the bolt backward against the tension of spring 5 and releases the shackle.

To prevent the formation of air or lubricant cushions in the recesses or sockets 10 and 11, particularly when oil or other lubricant is applied to the lock, I provide these 15 tumblers with recesses or passages, certain forms being shown. In Fig. 2, it takes the form of the central passage 16. In Fig. 3, these take the form of the grooves 17 in the 20 outside surface of the pin tumblers, these grooves being straight, while in Fig. 4, spiral grooves 18 are similarly provided. These are mere variations of the same broad 25 idea. In this connection, it is to be noted that I bevel the end edges of the pin tumblers as at 19, so that an annular passage is provided around the tumblers when 30 they are mounted in position. This of course facilitates the circulation or escape of the air or lubricant. The same idea may be 35 carried into effect, as shown in Fig. 5, by grooving the walls of the passages or sockets 10 and 11, as at 20, and having the pin tumblers with or without grooves or pas-

This invention permits the oil to pass readily around or about the pin tumblers and lubricates the walls of the passages or sockets 10 and 11, and at the same time, permitting 40 the escape of the air or lubricant so as to prevent the formation of the cushions referred to and do away with the incapacitation of the lock for use, due to lubrication.

What I claim is:

45 1. A cylinder lock including in combination, a bolt, a cylinder having means thereon for actuating the bolt, said cylinder being adapted to be actuated by key, said cylinder and the lock having a plurality of recesses or sockets normally in alinement, a plurality 50 of pin tumblers mounted in said recesses or sockets and normally held toward said cyl-

inder, and means provided in connection with said recesses or sockets and said pin tumblers to prevent the sealing of the recesses or sockets upon the application of a lubricant to said lock. 55

2. A cylinder lock including in combination, a bolt, a cylinder having means thereon for actuating the bolt, said cylinder being adapted to be actuated by key, said cylinder and the lock having a plurality of recesses or sockets normally in alinement, a plurality of pin tumblers mounted in said recesses or sockets and normally held toward said cylinder, said pin tumblers having passages so as to permit the escape of air and lubricant to prevent the sealing of said recesses or sockets upon the application of a lubricant to the lock. 60

3. A cylinder lock including in combination, a bolt, a cylinder having means thereon for actuating the bolt, said cylinder being adapted to be actuated by key, said cylinder and the lock having a plurality of recesses or sockets normally in alinement, a plurality of pin tumblers mounted in said recesses or sockets and normally held toward said cylinder, said pin tumblers having longitudinal 65 passages and also having transverse passages so as to permit the escape of air and lubricant to prevent the sealing of said recesses or sockets upon the application of a lubricant to the lock. 70

4. As an article of manufacture, a pin 75 tumbler of cylindrical shape adapted to be mounted in a socket or recess in the lock and having a longitudinal passage so that when a lubricant is applied to said lock, the recess or socket in which the pin tumbler is 80 mounted, will not be sealed. 90

5. As an article of manufacture, a pin 95 tumbler of cylindrical shape having its edges beveled so that by placing tumblers in juxtaposition to each other, an annular passage therearound is provided, said pin tumbler also having a longitudinal passage, said passages providing means for preventing the sealing of the sockets and recesses on the application of a lubricant to the lock. 100
